FIG. 4

FIG. 5

FIG. 6

UNITED STATES PATENT AND TRADEMARK OFFICE
CERTIFICATE OF CORRECTION

PATENT NO. : Des. 418,327
DATED : January 4, 2000
INVENTOR(S) : Patrick H. SULLINS et al.

It is certified that error appears in the above-identified patent and that said Letters Patent is hereby corrected as shown below:

Line 3, delete "FIG. 2 is a top view of the design of FIG. 7", and
insert --FIG. 2 is a top view of the design of FIG. 1--.

Line 4, delete "FIG. 3 is a front view of the design of FIG. 7", and
insert --FIG. 3 is a front view of the design of FIG. 1--.

Line 5, delete "FIG. 4 is a left side view of the design of FIG. 7", and
insert --FIG. 4 is a left side view of the design of FIG. 1--.

Line 7, delete "FIG. 5 is a back view of the design of FIG. 7", and
insert --FIG. 5 is a back view of the design of FIG. 1--.

Line 8, delete "FIG. 6 is a bottom view of the design of FIG. 7", and
insert --FIG. 6 is a bottom view of the design of FIG. 1--.

Signed and Sealed this

Fifteenth Day of May, 2001
